UNITED STATES PATENT OFFICE.

ALBERT E. HARTEL, OF PHILADELPHIA, PENNSYLVANIA, ASSIGNOR, BY MESNE ASSIGNMENTS, TO THE HARTEL LIGHT COMPANY, A CORPORATION OF DELAWARE.

GAS-BURNER.

SPECIFICATION forming part of Letters Patent No. 726,910, dated May 5, 1903.

Application filed May 9, 1902. Serial No. 106,589. (No model.)

To all whom it may concern:

Be it known that I, ALBERT E. HARTEL, a resident of Philadelphia, in the county of Philadelphia and State of Pennsylvania, have invented certain new and useful Improvements in Gas-Burners; and I do hereby declare the following to be a full, clear, and exact description of the invention, such as will enable others skilled in the art to which it app-

10 pertains to make and use the same.

My invention relates to an improvement in gas-burners, and more particularly to gas-burning lamps, the object of the invention being to provide an improved lamp in which 15 gas and air under pressure can be mixed, heated, and burned upon incandescent mantles, the products of combustion being utilized to heat the chamber in which the gas and air are mixed.

20 A further object is to provide an improved preheating-chamber into which gas is injected by air under greater pressure than the gas and provide means for insuring at all times an even pressure of air, and consequently an 25 even pressure of the mixture.

25 A further object is to provide a lamp with an improved preheating-chamber in which gas and air under pressure are heated by the otherwise waste products of combustion and 30 so construct the lamp as to compel the products of combustion to envelop the preheating-chamber.

With these objects in view the invention 35 consists in certain novel features of construction and combinations and arrangements of parts, as will be more fully hereinafter described, and pointed out in the claims.

In the accompanying drawings, Figure 1 40 is a view in section illustrating a lamp embodying my invention. Fig. 2 is an enlarged view in section of the injector. Fig. 3 is an enlarged view in section illustrating a regulator 28, and Fig. 4 is a diagrammatic view of the complete apparatus.

45 1 represents an approximately cylindrical lamp-casing, ornamented in any desired manner and flared at its lower end, as shown at 2, and partially closed by a cap or top 3 at its upper end, said cap so spaced from the 50 casing as to permit a free outlet of currents

through the lamp. Through the top 3 of this casing a gas-supply pipe 4 projects and is connected therewith by a suitable ring and thumb-screw 5 to support the top on the pipe, and the lower end of this gas-pipe 4 is externally screw-threaded and screwed into the top of a spherical injector-chamber 6, which latter is provided at one side with a downwardly-curved spout 7, screwed into the top of my improved inverted conical preheating-chamber 8 and preferably discharging therein to one side of its center, as clearly shown in Fig. 1. A main burner-tube 9 is screwed into the contracted lower end of preheating-chamber 8 and is screwed at its lower end 65 into a casting forming branch pipes 10, carrying burners 11, (preferably Bunsen burners,) on which are mounted incandescent mantles 12. Into the bottom of this casting 10 a short vertical pipe or rod 12^a is screwed 70 and is adapted to support an inverted conical perforated globe-holder 13, secured on tube 12^a by a set-screw 14 and supporting a globe 15, the upper end of the globe inclosed in the flared lower end 2 of casing 1, but not tight 75 thereagainst, a sufficient space being left between casing and globe to permit a free entrance of air at this point, as will be herein-after explained.

In casing 1 and surrounding preheating-chamber 8 a sleeve 16 is located and flared at its lower end to compel the hot products of combustion from the burners to entirely envelop the preheating-chamber in escaping from the lamp, and thereby intensely heat 85 said chamber. This sleeve 16 projects down beyond the juncture of the globe and casing, so as to direct the air entering at this point around the outside of the sleeve and create a suction through the sleeve to insure the passage therethrough of the products of combustion, and this separation of the globe and casing and the free entrance of cold air through the globe-holder 13 serves to maintain the globe cool and prevent its breaking due to the 90 heat of the burners.

To support the preheating-chamber 8 in proper position in the casing and sleeve and maintain the proper relative positions of the latter, screws or bolts 17 project through the 95

casing and sleeve and into or against the pre-heating-chamber, as clearly shown in Fig. 1.

A valve 18, having long arms 19 for the attachment of cords or chains to permit the easy operation of said valve, is located in gas-pipe 4 above the lamp-casing and is adapted to govern the supply of gas to the lamp. This gas-pipe may be connected with the gas-main and the gas be under the usual main-pressure or may be connected with a gas-generator and a suitable pressure-regulator provided for regulating the pressure of gas. A pilot-tube 20 connects with gas-pipe 4 above valve 18 and projects through the top 3 and down into the lamp-casing, where it terminates in a pilot-light 21 above the mantles 12, and as this pilot is intended to burn at all times it serves to light the burners whenever gas is turned on.

An air-supply pipe 22 extends down through the top 3 and is provided at its lower end with an injector-nozzle 23, projecting into injector-chamber 6 and partially through the latter across the gas-inlet and located to discharge into the spout 7. This air-pipe 22 preferably communicates with an air-reservoir 24 and the latter supplied with air by a motor 25 of any desired construction, and a suitable cock 26 is located in air-pipe 22 to shut off partially or entirely the supply of air.

Between this cock 26 and the injector-chamber 6, and preferably, though not essentially, located as shown, an air-pressure governor 27, of any well-known construction, is provided and adapted to maintain the air-pressure always uniform, which is essential to insure the steady burning of the lamp. The air is supplied to the injector at a pressure somewhat in excess of the gas-pressure. The exact difference in pressure may be varied by adjusting governor 27 to secure the best proportion of gas and air and the highest point of incandescence at the burners. By providing this injector, by means of which air under greater pressure than gas can inject the gas into the preheating-chamber, and thus permit these two gases of different pressure to be heated in chamber 8 in a thoroughly-mixed condition and under pressure, a light of great brilliancy is secured, and to govern the supply of the mixture to the burners and prevent a diminution of pressure in the preheating-chamber I provide regulators 28, located at the connection of burners 11 with branch pipes 10. Each regulator consists of an externally and internally screw-threaded hollow plug 29, screwed onto branch pipe 11 and made at its upper end into a contracted cylinder 30, having openings 31 in its side walls for the escape of the preheated mixture, and the upper end of this cylinder 30 is beveled or made conical, forming a needle-valve, to enter a contracted opening in an internally-threaded cap 32, screwed onto plug 29, and made with a milled flange 33 to facilitate the adjustment of this cap up and down, and hence the supply of heated mix-

ture to the burner. A jam-ring 34 is preferably provided on plug 29 to lock the cap in any position to which it may be adjusted.

The operation of my improvements is as follows: The valve 18 is turned to admit gas, which passes down through chamber 8 and tube 9 to the burners and is ignited by the pilot-light, which is preferably burning at all times. The pilot-light is preferably located so as to impart a certain amount of heat to the chamber and prevent its being thoroughly chilled. Air may now be turned on, it being supplied at even pressure (due to governor 27) and in excess of the gas-pressure. The discharge of the air into the injector-chamber 6 and directly into the gas therein serves to draw the gas with it through spout 7 into preheating-chamber 8, where the gas and air are thoroughly mixed and highly heated and passed with undiminished pressure to the burners, the regulators 28 preventing any diminution of pressure and regulating the supply of mixture to the burners. The hot products of combustion from the burners is directed up through sleeve 16 to compel the thorough enveloping of the chamber by the hot products to heat the same to a high degree and insure the thorough heating of the mixture.

While I have shown and described what I believe to be a preferred form of my invention, still many slight changes might be made in the structure and arrangement of parts without departing from my invention. For instance, the particular shape of the preheating-chamber is not essential, and it might, in fact, constitute a coil or coils of pipe, and a great many other changes might be made in the details of construction, and hence I do not wish to be limited to the precise construction set forth, but consider myself at liberty to make such slight changes and alterations as fairly fall within the spirit and scope of my invention.

Having fully described my invention, what I claim as new, and desire to secure by Letters Patent, is—

1. In a light-producing apparatus, the combination of a preheating-chamber in which a mixture of gas and air is preheated, an injector receiving and mixing and injecting gas and air in a mixed state into said preheating-chamber, a burner so arranged that it produces light by combustion thereof of said intermixed gas and air and also heats by the heat of its products of combustion said preheating-chamber, and a pipe connecting said preheating-chamber and said burner and which conveys mixed and preheated gas and air from said preheating-chamber to said burner.

2. In a light-producing apparatus, the combination of a preheating-chamber, an injector-chamber communicating with said preheating-chamber and supplied with gas under pressure, an air-supply pipe projecting into said injector-chamber and through which air

- under greater pressure than that of the said gas is discharged and there acts to inject mixed gas and air into said preheating-chamber, a burner so arranged that it produces 5 light by combustion thereat of said intermixed gas and air and also heats by the heat of its products of combustion said preheating-chamber, and a pipe connecting said preheating-chamber and said burner.
- 10 3. In a light-producing apparatus, the combination of a preheating-chamber, a mixing-injector communicating with said preheating-chamber, means that separately supply gas and air under pressure to said mixing-injector and from it in an intermixed state into 15 said preheating-chamber, an adjustable governor on the air-supplying means and which maintains a uniform flow of air into said mixing-injector and under a pressure greater than that of the gas in the gas-supplying means, a burner so arranged that it produces 20 light by combustion thereat of said gas and air and also heats by the heat of its products of combustion said preheating-chamber, 25 and a pipe connecting said preheating-chamber and said burner.
4. In a light-producing apparatus, the combination of a preheating-chamber, an injector-chamber communicating with said preheating-chamber, a pipe which supplies gas under pressure to said injector-chamber, a pipe which supplies air to said injector-chamber under pressure in excess of that of said gas, a burner so arranged that it produces 30 light by combustion thereat of said gas and air and also heats by the heat of its products of combustion said preheating-chamber, and a pipe connecting said preheating-chamber and said burner.
- 35 5. In a light-producing apparatus, the combination of a preheating-chamber, a mixing-injector which receives separately and mixes and injects gas and air under pressure and in a mixed state into said preheating-chamber, a burner-tube connecting with said preheating-chamber, a burner on said burner-tube so arranged that it produces light by combustion thereat of said intermingled gas and air and also heats by the heat of its products of combustion said preheating-chamber 40 and its gaseous contents, and a regulator in said burner-tube which governs the rate of

flow of said preheated gas and air mixture to said burner.

6. In a light-producing apparatus, the combination of pipes that supply gas and air under pressure, a preheating-chamber, a mixing-injector which receives and mixes and injects said gas and air in a mixed state into said preheating-chamber, a main burner, a burner-tube connecting said main burner and said preheating-chamber and which conveys said intermixed gas and air from said preheating-chamber to said burner, and with said preheating-chamber located in the zone of heat caused by the products of combustion of said gaseous mixture at said burner. 55

7. In a light-producing apparatus, the combination of a preheating-chamber, an injector-chamber communicating with the preheating-chamber and to which gas is supplied under pressure, an air-supply pipe projecting into the injector and through which air under greater pressure than the gas is discharged to inject the gas into the preheating-chamber, a burner to heat the preheating-chamber, and a pipe connecting said burner and preheating-chamber. 70

8. In a light-producing apparatus, the combination of a preheating-chamber, a spherical injector-chamber, a spout connecting said chambers, a pipe for supplying gas to the top of said injector-chamber, a pipe for air under pressure in excess of the gas-pressure, a nozzle on said air-pipe projecting into one 85 side of the injector-chamber opposite to the spout, a burner arranged to heat the preheating-chamber and a pipe connecting the preheating-chamber and burner.

9. In a lamp, the combination with a casing and a sleeve therein through which the products of combustion escape, of a preheating-chamber centrally located in said sleeve, means for supplying gas and air under pressure to said chamber, and a burner connected 90 with and adapted to heat said preheating-chamber. 95

In testimony whereof I have signed this specification in the presence of two subscribing witnesses.

ALBERT E. HARTEL.
